DOCTOR FRANKLIN OLIVER, OF OAKLAND, CALIFORNIA.

DOOR-BUFFER.

1,172,037.

Specification of Letters Patent. Patented Feb. 15, 1916.

Application filed June 5, 1914. Serial No. 843,165.

To all whom it may concern:

Be it known that I, DOCTOR FRANKLIN OLIVER, a citizen of the United States, and a resident of Oakland, in the county of Alameda and State of California, have invented a new and Improved Door-Buffer, of which the following is a full, clear, and exact description.

The object of the invention is to provide a new and improved door buffer which is very simple and durable in construction, easily attached to the door and wholly independent of the door lock, the door buffer being arranged to permit the door to close gently on slamming the door thus preventing injury to the door and door casing and reducing the shock incident to the slamming of the door to a minimum.

In order to accomplish the desired result use is made of a brake mechanism, an oscillating member, and means for actuating the said mechanism by the said oscillating member on slamming the door, the said oscillating member oscillating free of the brake mechanism on closing the door with ordinary force.

A practical embodiment of the invention is represented in the accompanying drawings forming a part of this specification, in which similar characters of reference indicate corresponding parts in all the views.

Figure 1 is a sectional side elevation of the door buffer as applied to a door and door casing, the section being on the line 1—1 of Fig. 3; Fig. 2 is a plan view of the same with the striking mechanism on the door casing omitted; Fig. 3 is a sectional plan view of the same; Fig. 4 is a cross section of the same; Fig. 5 is a sectional plan view of the same with the parts in working position on slamming the door; and Fig. 6 is a face view of the striker on the door casing.

The casing A of the door buffer is let in and fastened to the top rail of the door B, as plainly shown in the drawings, and on the casing A is held a vertically disposed pivot C on which is mounted to swing an actuating member D, preferably of L shape and having its forward end extending into an opening A' in the front plate of the casing A (see Figs. 1, 2 and 3). The forward end of the actuating member D is adapted to be engaged by a striking pin E arranged on the plate E' secured to the head jamb of the door casing B', as plainly indicated in Fig. 1. It will be noticed that when the door B is

closed the free end of the actuating member D is swung inwardly in the direction of the arrow a' (see Figs. 3 and 5).

On the pivot pin C is mounted to swing and to slide a movable brake member F operating in conjunction with a segmental brake member G fixed in the casing A. The movable brake member F is preferably of U shape, and between its side bars oscillates the actuating member D, and the free ends F' of the movable brake member F are beveled (see Fig. 4) and adapted to move in frictional contact with the beveled side edges G' of the segmental face of the fixed brake member G. Normally the movable brake member F has its beveled edges F' free of the beveled edges G' of the fixed member G, but when the door is slammed the movable brake member F is caused to slide radially as hereinafter more fully described to engage the beveled edges F' with the beveled edges G'. The pivot pin C extends through elongated slots F² formed in the side bars of the movable brake member F to allow the latter to slide in a radial direction. On the side bars of the movable brake member F is secured a pin H extending through a slot D' formed in the forward end of the actuating member D, and the said pin H is pressed on by one end of a spring I held in the slot D' and seated at the forward end thereof, the spring having its outer portion coiled around a pin J attached to the free end of the actuating member D. By the arrangement described the spring I is held in place in the slot D' to press at all times against the pin H. A spring K is connected at one end with the pivotal end of the actuating member D and the other end of the spring is attached to the fixed brake member G so as to hold the actuating member D normally in a forward position, as shown in Figs. 1, 2 and 3.

The operation is as follows: When the door B is closed with ordinary force and the actuating member D finally strikes the striking pin E then the actuating member D is swung in the direction of the arrow a' against the tension of its spring K, and the swinging motion of the actuating member D is transmitted by the spring I and pin H to the brake member F to swing the latter in the same direction as the actuating member D and without the beveled edges F' being in contact with the beveled edges G' of the fixed brake member G. When the door is

opened the spring K returns the actuating member D and the brake member F to their normal position shown in Figs. 1, 2 and 3. When the door B is closed with more than ordinary force then the sudden impact of the actuating member D on the striking pin E causes a sudden movement of the actuating member D in the direction of the arrow a' , and in doing so the spring I is pressed, the wall of the slot D' of the actuating member D bears on and moves the pin H, and the movable brake member F is not only caused to swing with the actuating member D but is also caused to slide radially in the direction toward the fixed brake member G so that the beveled edges F' of the movable brake member F frictionally engage the beveled edges G' of the fixed brake member G, and consequently the swinging movement of the movable brake member F and that of the actuating member D in the direction of the arrow a' is retarded by the braking action of the member F on the member G.

By the arrangement described the brake mechanism is brought into action to cushion the door in case the latter is slammed with more than ordinary force, but when the door is closed with ordinary force or speed then the brake mechanism remains inactive as the movable brake member F swings free relative to the fixed brake member G.

The pin J is preferably adjustably mounted in the actuating member D and for this purpose the outer end of the pin is threaded (see Fig. 1) and screws in the free end of the actuating member D. By this arrangement the pin J can be screwed farther in when the buffer is used on light doors or outward when the buffer is used on heavy doors. In either case the pin J serves to limit the movement of the pin H relative to the pin J to prevent the brake member F from too forceful engagement with the brake member G.

Having thus described my invention, I claim as new and desire to secure by Letters Patent:

1. A door buffer, comprising a brake mechanism having a fixed member and a movable member mounted to swing, and means for actuating the said movable member on slamming the door to move the same into engagement with the fixed member, the said movable member swinging free of the fixed member of the brake mechanism on closing the door with ordinary force.

2. A door buffer, comprising a brake mechanism having a fixed and a movable member normally free of the said fixed member, an oscillating member, and means for moving the said movable brake member by the said oscillating member into engagement with the said fixed brake member on slamming the door.

3. A door buffer, comprising a friction

brake having a segmental fixed brake member and a movable brake member normally mounted to swing free of the said fixed brake member on closing the door with ordinary force, and means for engaging the said movable brake member with the said fixed brake member on slamming the door.

4. A door buffer, comprising a friction brake having a fixed segmental brake member and a movable brake member mounted to swing normally free of the said fixed brake member, and an actuating member controlled by the closing of the door and arranged to allow the said oscillating brake member to swing free of the fixed brake member on closing the door with ordinary force and to move the said oscillating brake member into frictional engagement with the said fixed brake member on slamming the door.

5. A door buffer, comprising a friction brake having a fixed segmental brake member and a movable brake member normally free of the said fixed brake member and adapted to engage the same, the movable brake member being capable of swinging and sliding radially, an actuating member mounted to swing on the axis of the said movable brake member and independently thereof, striking means adapted to engage the said actuating member on closing the door, and means connecting the said movable brake member with the said actuating member to move the movable brake member radially into engagement with the fixed brake member on slamming the door.

6. A door buffer, comprising a friction brake having a fixed segmental brake member and a movable brake member normally free of the said fixed brake member and adapted to engage the same, the movable brake member being capable of swinging and sliding radially, an actuating member mounted to swing on the axis of the said movable brake member and independently thereof, the said actuating member having a slot, a pin held on the movable brake member and extending through the said slot, a spring interposed between the said pin and the said actuating member, and striking means adapted to engage the said actuating member on closing the door.

7. A door buffer, comprising a friction brake having a fixed segmental brake member and a movable brake member normally free of the said fixed brake member and adapted to engage the same, the movable brake member being capable of swinging and sliding radially, an actuating member mounted to swing on the axis of the said movable brake member and independently thereof, the said actuating member being approximately L shape and having a slot, a spring pressing the said actuating member, a pin held on the said movable brake mem-

ber and extending through the said slot, a spring interposed between the said pin and the said actuating member, and striking means adapted to engage the said actuating member on closing the door.

8. A door buffer provided with a fixed segmental brake member having beveled sides, an approximately U-shaped movable brake member mounted to swing and to 10 slide radially, the free ends of the said movable brake member being beveled and adapted to engage the beveled edges of the said fixed brake member, and actuating means connected with the said movable

brake member to impart a swinging motion 15 thereto on gently closing the door and to impart a swinging and sliding motion to the said movable brake member to frictionally engage the latter with the said fixed brake member on slamming the door.

In testimony whereof I have signed my name to this specification in the presence of two subscribing witnesses.

DOCTOR FRANKLIN OLIVER.
